DESIGN FOR A CLOTHES-DRYING RACK

Kenneth E. Luger, Minneapolis, Minn.

Application May 7, 1943, Serial No. 110,141

Term of patent 7 years

To all whom it may concern:

Be it known that I, Kenneth E. Luger, a citizen of the United States, residing at Minneapolis, in the county of Hennepin and State of Minnesota, have invented a new, original, and ornamental Design for a Clothes-Drying Rack, of which the following is a specification, reference being had to the accompanying drawing, forming part thereof.

Referring to the drawing, the single figure of the drawing is a perspective view of a clothes-drying rack showing my new design.

I claim:

The ornamental design for a clothes-drying rack, as shown.

KENNETH E. LUGER.
